ROCK DRILL

John C. Curtis, Garfield Heights, Ohio, assignor
to The Cleveland Rock Drill Company, Cleve-
land, Ohio, a corporation of Ohio

Application May 26, 1933, Serial No. 673,051

11 Claims. (Cl. 121—9)

This invention relates broadly to rock drills, but more particularly to rock drills equipped with a fluid actuated feeding mechanism.

Heretofore rock drills equipped with a fluid actuated feeding mechanism were provided with a device permitting to reduce the feeding power of the mechanism at the will of the operator. For instance, when rotative movement of the cutting tool became restrained, it was possible to 10 reduce the power of the feeding mechanism, by venting some of the pressure fluid from the mechanism to the atmosphere. No provisions were made to reduce the force of the blows distributed to the cutting tool by the working piston. With 15 such a construction, even though the feeding power of the mechanism was reduced, the cutting tool was still driven deeper into the material. To prevent this undesirable feature, the operator was compelled to bleed the feeding mechanism 20 sufficiently to prevent the hammer from distributing its blows to the cutting tool. These blows, however, were distributed to the front portion of the machine, thus causing the breakage thereof and increasing the cost of operation.

25 The main object of this invention is to provide means whereby the feeding power of the feeding mechanism together with the force of the blows distributed to the cutting tool, may be reduced at the will of the operator.

30 Other objects more or less ancillary to the foregoing, and the manner in which the object is realized will appear in the following description, considered in connection with the accompanying drawings, set forth the preferred embodiment of 35 the invention.

In the drawings:

Fig. 1 illustrates a longitudinal cross sectional view of a rock drill of the stoker type embodying the invention, the parts thereof being shown in 40 normal operating position.

Fig. 2 is an enlarged cross sectional view taken in a plane indicated by line 2—2 in Fig. 1, showing the valve in closed position.

45 Fig. 3 is a view similar to Fig. 1, illustrating the different parts moved into another position.

Fig. 4 is a view similar to Fig. 2, illustrating the valve in open position.

Referring to the drawings in which like characters designate corresponding parts throughout the several views, 10 represents the cylinder of a rock drill, having a piston 11 reciprocably mounted therein. Mounted into the front end of the cylinder 10, there is a front housing adapted to 50 slidably but non-rotatably receive the shank 12

of a cutting tool upon which the piston 11 is free to deliver its blows. The back end of the cylinder 10 is enlarged to accommodate a valve block 13, and the cylindrical portion 14 of a head 15. Reciprocably mounted within the valve block 13, there is a fluid actuated valve 16 capable of engagement with opposed annular valve seats 17, for controlling the admission of the pressure fluid into the cylinder. The valve block 13 is provided with a plurality of passages 18 leading from one 65 face of the valve into the rear end of the cylinder. Similarly the cylindrical portion 14 of the head 15, is provided with a plurality of passages 19 leading from a chamber 20 to the valve 16, and other passages 21 leading from the valve 16 into the front end of the cylinder. To permit the exhaust of the pressure fluid from the cylinder, the latter is equipped with a duality of exhaust 70 passages 22, opening into a deflecting exhaust port 23.

Formed within the back head 15, there is a tapered socket adapted to receive the corresponding end of a handle 24, secured therein by means of a nut 25. This handle may be grasped by the operator for rotating the machine assembly and consequently rotating the cutting tool. Within the handle there is provided an enlarged lubricant reservoir 26, which may be filled at will by removing a screw threaded plug 27.

Disposed near the outer end of the handle 24, the latter is formed with a screw threaded bore 28, the bottom thereof constituting a chamber 29. Secured in screw tight engagement within the bore 28, there is a plug 30 adapted to slidably receive the stem 31 of a valve 32. One end of this stem is formed with a knob 33 protruding from the plug 30, upon which manual pressure may be applied to operate the valve. Adjacent the valve 32, the plug 30 is formed with a valve seat formed by the outer edge of an enlarged orifice 34, which is in constant communication with the atmosphere through a plurality of passages 35. The valve 32 is normally held against its seat by the effort of a compression spring 36 disposed within the chamber 29.

Formed within the head 15, there is a valve chamber 37 having reciprocably mounted therein a spool valve 38. This chamber is closed at one end by a screw threaded plug 39 adapted for engagement with the valve 38 to limit the stroke thereof in one direction. Interposed between one end of the valve 38 and the bottom of the chamber 37, there is a compression spring 40, the purpose of which will be explained later.

Secured to the rear end of the head 15, there is 110

the feeding mechanism comprising a feed tube 41 having a piston and piston rod 42 and 43, slidably mounted therein. Since this mechanism is common to tools of the type described, no further explanation is thought necessary.

Rotatably mounted within the head 15, there is a throttle valve 44 formed with a bore 45 through which pressure fluid may be admitted from its source of supply. Leading from the bore 45 to the circumferential valve of the throttle valve, there is a plurality of radially disposed passages 46, 47, and 48. The passage 46 is capable of communication with the chamber 20 for admitting pressure fluid therein, while the passage 47 is capable of communication with the interior of the air feed cylinder 41 through passage 49, annular groove 50, and passage 51. Similarly, the passage 48 is capable of communication with the valve chamber 37 through the passage 52, annular groove 53 and passage 54. Again this valve chamber 37 is in constant communication with the chamber 29 formed in the handle 24, through a passage 55, annular groove 56, and passage 57. Leading from the air feed cylinder 41 into the valve chamber 37, there is a passage 58. To permit the communication of this last passage with the rear end of the cylinder 10, the valve 38 is formed with an annular groove 59, thus affording the communication of the passage 58 with a passage 60, annular groove 61, and passage 62. The lubricant from the reservoir 26 may be admitted into the throttle valve bore 48 through a passage 63.

During the normal operation of the machine, assuming the throttle valve 44 to be positioned as illustrated in Fig. 1, pressure fluid is admitted into the chamber 20 to be distributed by the valve 16 into both ends of the cylinder 10 to actuate the piston 11. When the valve 16 is positioned as illustrated in the drawings, pressure fluid is admitted into the front end of the cylinder 10 to drive the piston 11 rearwardly. During the rearward travel of the piston, the exhaust ports 22 will be covered by the latter, thus compressing the atmosphere in the rear end of the cylinder, and creating pressure on the valve 16. The operation and shifting of this valve being the same as the operation of the valve described in my pending application Serial No. 573,931, no further explanation is thought necessary other than mentioning the fact that the valve 16 is thrown rearwardly by compression admitted thereto through the passages 18. When the valve 16 is shifted in its rearmost position, motive fluid is admitted into the rear end of the cylinder through the passages 18 to drive the piston 11 forwardly, thus limiting the rearward stroke of the piston. The valve is designed in such a manner as to return the piston forwardly just before the latter reaches the valve block 13, permitting thereby the stroke of the piston to be about equal to the free space in the cylinder. During the normal operation of the machine, pressure fluid is also admitted into the air feed cylinder from the throttle valve 44 through the passages 47 and 49, annular groove 50, and passage 51, to act on the feed piston 42 and drive the machine upwardly or toward the work. Simultaneously, pressure fluid is admitted from the throttle valve in the valve chamber 37 through the passages 48 and 52, annular groove 53, and passage 54, to act on the valve 38 and maintain the latter toward the right, against the tension of the spring 40, or in the position illustrated in Fig. 1. When the valve is in this position, it will be seen that

the communication of the passage 58 with the port 60 is shut off, thus preventing pressure fluid to flow from the air feed cylinder into the rear end of the cylinder 10. In this position of the valve 38 the hand operated valve 32 is maintained against its seat by the tension of the compression spring 36, thus preventing the communication of the chamber 29 with the atmosphere through the passage 35.

When the cutting tool becomes stuck in the drilled hole, manual pressure may be applied on the knob 33 to open the valve 32. Pressure fluid still admitted into the valve chamber 37 will now escape to the atmosphere through the passage 55, annular groove 56, passage 57, chamber 29, and passages 34 and 35, thus relieving the pressure acting on the valve 38, and permitting the shifting thereof toward the left by the tension of the spring 40. In this position of the valve 38, pressure fluid will be admitted into the back of the cylinder 10 through the passage 58, valve, annular groove 59, passage 60, annular groove 61, and passage 62. This additional amount of pressure fluid admitted in the rear end of the cylinder 10, will, during the rearward movement of the piston, be compressed by the piston and cause a premature shifting of the valve 16. The premature shifting of the valve will permit the admission of the pressure fluid into the rear end of the cylinder, thus preventing a complete stroke of the piston, and consequently reducing the force of the blows delivered to the cutting tool. During the forward movement of the piston, the latter will uncover one of the exhaust passages 22, permitting thereby the pressure fluid in the rear of the cylinder and consequently a portion of the motive fluid from the air feed cylinder to exhaust to atmosphere, thus reducing the feeding power. It will be seen that the feeding power of the feeding mechanism is reduced every time the piston uncovers the exhaust passages, while the stroke of the piston is limited by the pressure fluid flowing from the air feed cylinder.

When it is desired to resume the normal operation of the machine, the operator may relieve the pressure previously applied on the knob 33, thus permitting the valve 32 to be shifted, by the action of the spring 36, against its seat, and closing the passage 34. The pressure admitted into the valve chamber 37 through the passage 54, will again shift the valve toward the right as previously explained.

Although the foregoing description is necessarily of a detailed character, in order to completely set forth the invention, it is to be understood that the specific terminology is not intended to be restrictive or confining and it is to be further understood that various rearrangements of parts and modification of the structural detail may be resorted to without departing from the scope or spirit of the invention as herein claimed.

I claim:

1. In a rock drill, the combination of a cylinder having a fluid actuated piston reciprocable therein, of a fluid actuated feeding mechanism for said rock drill, and of means for reducing the feeding power of said mechanism and simultaneously reducing the stroke length of said piston within said cylinder.
2. In a rock drill, the combination of a cylinder having a fluid actuated piston reciprocable therein, of a tool adapted to receive the striking blows of said piston, of a fluid actuated feeding mechanism for said rock drill adapted to feed said

- tool to the work, and of means for reducing the feeding power of said mechanism and simultaneously reducing the striking power of said piston on said tool.

5. In a rock drill, the combination of a cylinder having a fluid actuated piston reciprocable therein, of a tool adapted to receive the striking blows of said piston, of a fluid actuated feeding mechanism for said rock drill adapted to feed said tool to the work, of a throttle valve for controlling the admission of the pressure fluid into said cylinder and said mechanism, and of means independent of said throttle valve for reducing the feeding power of said mechanism and reducing the striking power of said piston on said tool.

10. In a rock drill, the combination of a cylinder having a fluid actuated piston reciprocable therein, of a fluid actuated feeding mechanism for said rock drill, of means for controlling the admission of the pressure fluid into said cylinder to actuate said piston, and of other means for permitting or preventing an additional amount of pressure fluid to be admitted from said feeding mechanism into one end of said cylinders.

15. In a rock drill, the combination of a cylinder having a fluid actuated piston reciprocable therein, of a valve block having a fluid actuated valve reciprocable therein for controlling the admission of the pressure fluid into said cylinder to actuate said piston, the shifting of said valve in one direction being responsive to the action of fluid compressed by said piston within one end of said cylinder, of a throttle valve for controlling the admission of the pressure fluid into said valve block, and means independent of said fluid actuated valve and said throttle valve for controlling the admission of a supplemental amount of pressure fluid into said one end of said cylinder to cause the premature shifting of said valve into said direction, reducing thereby the length of the stroke of said piston.

20. In a rock drill, the combination of a cylinder having a fluid actuated piston reciprocable therein, of a fluid actuated valve for controlling the admission of the pressure fluid into said cylinder to actuate said piston, the shifting of said valve in one direction being responsive to the action of fluid compressed by said piston within one end of said cylinder, of a fluid actuated feeding mechanism for said rock drill, means for admitting motive fluid into said mechanism, and means independent of said valve for admitting pressure fluid from said feeding mechanism into said one end of said cylinder to cause a premature shifting of said valve into said direction, reducing thereby the length of the stroke of said piston, the pressure fluid from said feeding mechanism being subsequently exhausted from said cylinder, thus reducing the feeding power of said feeding mechanism.

25. In a rock drill, the combination of a cylinder having a fluid actuated piston reciprocable therein, of a fluid actuated feeding mechanism for said rock drill, of means for exhausting the pressure fluid from said feeding mechanism into said cylinder, said means comprising a passage, an exhaust controlling valve subjected to the action of the pressure fluid admitted thereon for normally closing said passage, a port for exhausting the pressure fluid acting on said exhaust controlling valve for permitting the shifting of the latter in a position for opening said passage, and means associated with said exhaust controlling valve for shifting and holding the latter in the open position.

30. In a rock drill, the combination of a cylinder having a fluid actuated piston reciprocable therein, of a fluid actuated feeding mechanism for said rock drill, of independent passages for admitting pressure fluid into said cylinder to actuate said piston and into said feeding mechanism to operate the latter, and of means for admitting a supplemental amount of pressure fluid into one end of said cylinder and simultaneously exhausting an equal amount of pressure fluid from said feeding mechanism.

35. In a rock drill, the combination of a cylinder having a fluid actuated piston reciprocable therein, of a fluid actuated feeding mechanism for said rock drill, of unitary means for controlling the normal admission of the pressure fluid into said cylinder and said feeding mechanism, and of other means for controlling the admission of a supplemental amount of pressure fluid into said cylinder and simultaneously controlling the exhaust of an equal amount of pressure fluid from said feeding mechanism.

40. In a rock drill, the combination of a cylinder having a fluid actuated piston reciprocable therein, of a fluid actuated feeding mechanism for said rock drill, of unitary means for controlling the normal admission of the pressure fluid into said cylinder and said feeding mechanism, and of other means for controlling the admission of a supplemental amount of pressure fluid into said cylinder and simultaneously controlling the exhaust of an equal amount of pressure fluid from said feeding mechanism.

45. In a rock drill, the combination of a cylinder having a fluid actuated piston reciprocable therein, of a fluid actuated feeding mechanism for said rock drill, of unitary means for controlling the normal admission of the pressure fluid into said cylinder and said feeding mechanism, and of other means for controlling the admission of a supplemental amount of pressure fluid into said cylinder and simultaneously controlling the exhaust of an equal amount of pressure fluid from said feeding mechanism.

50. In a rock drill, the combination of a cylinder having a fluid actuated piston reciprocable therein, of a fluid actuated feeding mechanism for said rock drill, of unitary means for controlling the normal admission of the pressure fluid into said cylinder and said feeding mechanism, and of other means for controlling the admission of a supplemental amount of pressure fluid into said cylinder and simultaneously controlling the exhaust of an equal amount of pressure fluid from said feeding mechanism.

55. In a rock drill, the combination of a cylinder having a fluid actuated piston reciprocable therein, of a fluid actuated feeding mechanism for said rock drill, of unitary means for controlling the normal admission of the pressure fluid into said cylinder and said feeding mechanism, and of other means for controlling the admission of a supplemental amount of pressure fluid into said cylinder and simultaneously controlling the exhaust of an equal amount of pressure fluid from said feeding mechanism.

60. In a rock drill, the combination of a cylinder having a fluid actuated piston reciprocable therein, of a fluid actuated feeding mechanism for said rock drill, of unitary means for controlling the normal admission of the pressure fluid into said cylinder and said feeding mechanism, and of other means for controlling the admission of a supplemental amount of pressure fluid into said cylinder and simultaneously controlling the exhaust of an equal amount of pressure fluid from said feeding mechanism.

JOHN C. CURTIS. 135
